ENVELOPE OPENER

Edmund C. Metzger, Chicago, Ill.

Application May 11, 1945, Serial No. 593,127

12 Claims. (Cl. 30—294)

1

This invention relates to improvements in combined pencil sharpener and envelope opener, and one of the objects is to provide an improved simple and efficient device of this character, which may be readily carried in the pocket or employed as a desk tool, and which embodies a cutting blade that is used as both the pencil sharpening means and the means for severing an edge of an envelope to open the latter, the cutting edge of the blade being protected so as not to cause any injury.

A further object of the invention is to provide an improved device of this character, in which a razor blade may be employed as the cutting means, and in which device means are also provided whereby the cutting portion of the blade may be adjusted to accommodate envelopes of different sizes and thicknesses, and to vary the area in which the envelope is to be cut.

A further object of the invention is to provide an improved device of this character, in which the edge of the envelope to be cut will be drawn across the cutting area of the blade in an inclined position with respect to such edge, thereby facilitating the operation of the device.

A still further object of the invention is to provide improved means for clamping the blade and varying the curvature thereof to accommodate envelopes of different sizes.

To the attainment of these ends, and the accomplishment of other new and useful objects as will appear, the invention consists in the features of novelty in substantially the construction, combination and arrangement of the several parts, hereinafter more fully described and claimed, and shown in the accompanying drawings illustrating the invention, in which

Fig. 1 is an end view of a device of this character, constructed in accordance with the principles of this invention.

Fig. 2 is a top plan view of the structure shown in Fig. 1.

Fig. 3 is an end view similar to Fig. 1, but showing the reverse end of the device.

Fig. 4 is a sectional view taken on line 4—4, Fig. 2, showing the blade in position before it is compressed.

Fig. 5 is a longitudinal sectional view of the sharpener body, taken on line 5—5 Figure 2 with parts omitted.

Fig. 6 is an enlarged sectional view of the structure, showing the blade in convex position, but with the winged clamping nut removed.

Fig. 7 is a side elevation of the winged clamping nut.

Fig. 8 is an end elevation of the clamping nut.

2

Fig. 9 is a detail sectional view of an envelope, showing the way it is cut or opened by this device.

This invention provides means for utilizing new and used razor blades in a combined pencil sharpener and envelope opener, by curving the blade to give it strength and rigidity, and also to vary the curvature to accommodate envelopes of different sizes and thicknesses, and at the same time to provide a sharpening edge for a pencil receiving and guiding bore.

Referring now more particularly to the drawings, a holder body 20 of metal, plastic, or any suitable material which may be generally rectangular in form and only slightly larger than the well-known type of razor blades, is provided with a central longitudinally extending convex blade receiving surface 21, with angular guide-ways 22 extending across the corners of the body at the sides of the convex surface 21, the lower edges of the guide-ways extending below the side edges of the surface 21. At one end of the body is a conical bore 23 extending longitudinally of the body and at one edge of the convex surface 21, forming a guide-way for receiving the end of a pencil.

A blade 24 is disposed on the convex top surface 21, and has opposite cutting edges 25 which overlap the envelope guide-ways 22 and the upper edge of the bore 23 for engagement with envelopes and pencils inserted therein. A clamping plate 26 is applied over the blade, and has a lower concave surface conforming to the upper convex surface 21, so that by compressing the locking plate, the blade may be curved more or less, and locked in a fixed convex position. This locking plate has a central aperture 27 and inclined cam surfaces 28 extending around the aperture 27. At opposite ends of the aperture 27, and longitudinally of the plate, are aperture extensions 29, the aperture and extensions registering, generally, with openings in the blade 24.

A central bore 30 is provided in the body, having a conical recess 31 at the lower or under side, in which are seated a stem 32 having an upper portion 33 of reduced size, and a conical nut 34 secured to a lower threaded end 35 of the stem. This stem projects upwardly through the blade and through the locking plate 26, the reduced portion 33 extending above the inclined cam surfaces 28 and having a collar 36 secured to the upper end of the stem, as by a cross pin 37.

Mounted on the reduced portion of the stem is a winged nut 38 having opposite inclined engaging surfaces 39 at its lower edges for engaging the inclined cams 28. This winged nut is sub-

stantially flat, so that when moved longitudinally of the locking plate 26, it will pass with the stem through the aperture 27 and the aperture extensions 29 of the locking plate, to permit the insertion and removal of a blade and the locking plate, without removing the winged nut.

An envelope 40 to be opened, is inserted in one of the angular guide-ways 22, and is moved to the bottom of the guide-way and drawn lengthwise thereto, in contact with one of the cutting edges 25 of the blade, the blade producing a slit 41 at one side of the edge of the envelope, as shown more clearly in Fig. 9, without coming in contact with or damaging a sheet 42 or other material contained in the envelope. The curvature of the blade may be adjusted toward or from the bottom of the envelope receiving guide-ways 22 by relieving the pressure on the winged nut 38, thereby allowing the edge of the blade to be raised, as indicated in the broken outline in Fig. 6. With this adjustment, the envelope opener may be varied to accommodate envelopes of different sizes and thicknesses, and envelopes having more or less contents. The angular guide-ways 22 may be varied somewhat with respect to the cutting edges 25 of the blade, so that they will accommodate envelopes of different sizes and thicknesses.

In this construction, it is apparent that the cutting blade is given additional strength and rigidity by curving it transversely, and locking it firmly against a flat or curved supporting surface. The curvature of the blade may be varied to vary the contact of the blade with an envelope to be opened or with a pencil to be sharpened. The device is compact and easily operated and adjusted, the edges of the blade being protected at all times so that the device may be safely carried in a pocket or any place desired, without danger of injury. When the blade becomes dull, it is a simple matter to remove it and insert another one.

While the preferred form of the invention has been herein shown and described, it is to be understood that various changes may be made in the details of construction and in the combination and arrangement of the several parts, within the scope of the claims, without departing from the spirit of this invention.

What is claimed as new is:

1. A device of the class described comprising a substantially rectangular body having upstanding longitudinal edge portions, a blade supporting area between said edge portions having the upper surface thereof transversely convex, the upper surface of said area being below said edge portions, a longitudinal channel at each side of said

blade supporting area connecting said area with said edge portions, a blade adjustably mounted on said area and having the longitudinal cutting edge portions thereof extending into said channels, and an envelope guideway in each of said edge portions located diagonally with respect to said edge portions and intersecting the adjacent channel at one end thereof, said guideways also disposed angularly with respect to said channels so that a side of each of said guideways tapers downwardly from the upper side of the edge portion in which it is located, whereby to properly guide an envelope being drawn through a guideway, and means to adjust the position of the cutting edges of said blade in said channels to compensate for envelopes of different thicknesses.

2. A device of the class described comprising a substantially rectangular body having upstanding longitudinal edge portions, a blade supporting area between said edge portions having the upper surface thereof transversely convex, said edge portions extending upwardly beyond said blade supporting area, a blade removably mounted on said area having a longitudinal cutting edge parallel to and adjacent one of the upstanding edges, an envelope guideway located diagonally through one of said upstanding edge portions and extending through one end of said body, the bottom of said guideway being below the surface of said blade supporting area, and one of the faces of said guideway tapering downwardly and inwardly from the top of the edge portion toward said blade supporting area, whereby to properly guide an envelope through said guideway.
